GARMENT PRESS

Application filed July 2, 1924. Serial No. 723,740.

This invention relates to garment laundry pressing machines and particularly to improvements in power presses for imposing high pressure on the work.

5 An object is to produce a pressing machine capable of being converted to either a power press or foot operated press thereby enabling the manufacturer to assemble a power press or purely foot operated press 10 from the same manufactured parts which diminishes production difficulties in factories.

Another object of the invention is to produce improvements in power pressing machines whereby wide laterally opening jaws 15 are provided without resulting angular spreading movement thereby avoiding wide vertical separation of the pressing members which is undesirable because it permits the operator to accidentally injure his fingers in 20 the jaws; and for the purpose of illustrating my invention, I have chosen V-shaped pressing jaws ordinarily used for ironing cuff and neck bands of shirts, but it is understood that the principle of my invention together with 25 its structure may as well be applied to pressing machines having flat large area wide opening pressing members.

In order to illustrate the principle of the invention, there is shown an example of 30 an operator actuated press and a power press. The operator actuated press is a foot power machine, and the power press is a fluid expansion motor press.

The first three views show the power press 35 while the last view shows a foot press.

Figure 1 illustrates a side view of the pressing machine in open position; and Figure 2 also illustrates a side view thereof in 40 closed position with the near side of the frame removed to expose parts of the machine.

Figure 3 shows a front view of the pressing machine in closed position and just prior to application of high pressure by the motor means.

45 Figure 4 shows a modified form of the invention, being a view of the foot operated press having the improved fluid pressure diaphragm motor removed therefrom and replaced by a toggle anchor bracket.

The frame of the machine may consist of

parallel side pieces 10 assembled on a base 11 and which rise vertically and are provided with bolting flanges 12 at the top thereof. This construction affords a wide open clear space within the frame of the machine to 55 assemble the pipe system and moving parts of the machine. For the purpose of illustrating the present invention, I have chosen V-shaped cuff and neck band press jaws, but it is understood that a flat garment support 60 or buck may as well be anchored to the bolting flanges 12. Similarly the head may as well be flat, for the improved operating mechanism herein described is as well adapted to move a flat head back and forth across the 65 buck as the V-type cuff and neck band jaw herein disclosed. The present foot operated press closing means is well adapted to close V-type press jaws and requires little 70 space.

As already described, the present construction is well adapted to ironing presses of the cuff and neck band type for laundry shirt work; and to this end a buck 13 is anchored on the top of the frame. A movable head 14 75 is superimposed thereabove and adapted to swing laterally across and over the head 13 and after the head and buck have reached aligned pressing position, the two pressing members 13 and 14 are tightly drawn together under high pressure by motor means in one instance or foot operated means in another case. A feature of the construction is the provision of slight separating jaw clearance at the pressing plane, which is to 80 say clearance exists between the pressing surfaces of the two press jaws 13 and 14 in order that they move back and forth relatively one with the other. The pressing head and buck are suitably heated as by steam, and 85 a pipe 15 conveys steam to the press buck 13 while a pipe 16 provides a discharge or return steam pipe leading back to a boiler, and this pipe 16 may also connect with a fluid pressure motor which is used for producing 90 high jaw pressure.

A substantially long press lever link or arm 18 is disposed upright and if desired in parallel alignment with the vertical axis of the frame and reaches up and around the 95

pressing rear of the members and has its integral flange 19 bolted or screw fastened to the head 14. The lower end of this upright lever extends forwardly into the frame as at 5 20 and carries a compound motion fulcrum pin 21 the axis of which, when the press is closed, is preferably coincident with the vertical longitudinal axis of the frame 10. The press lever 18 undergoes a compound motion 10 and is adapted to perform the double purpose of first lifting upwardly on the head 14 to obtain clearance space between the head and buck, and thereafter the said lever is 15 adapted to swing laterally, the upper end 19 moving rearwardly with the lower end 20 moving forwardly; and to this end the combination draw or pull link lever 18 is provided with a compound motion fulcrum pin 22 intermediate the lever ends 19 and 20 and is 20 preferably located about half-way between the lever ends, or as shown in the drawings it is located slightly below the half-way point of the lever.

The lever 18 standing vertically with the 25 weight of the head 14 at the top thereof, constitutes in effect an inverted over-balanced pendulum which is poised sensitively above the fulcrum center 22. The press opens wide as shown in Figure 1 by permitting the head 30 14 to swing rearwardly, and readily moves forwardly again under the slightest effort applied by the operator. The ease with which the head 14 moves back and forth on the long vertical support lever 18 is characteristic 35 of this type of pressing machine because of the fact that, in the design of the press, advantage is gained by locating the center of gravity high above and directly over the fulcrum point 22 which renders the 40 head 14 quite sensitive to swinging motion and therefore the operator closes and opens the press with little effort.

A support lever or movable pivot compound motion bearing, in this instance a bell 45 crank lever, having a lower short arm 24 and a longer upper arm 25 is pivoted at 23 on the frame. One arm pivotally supports the lever 18 by connecting with the fulcrum pin 22; and the other lever arm is connected to 50 the frame by a tension spring 26 which is designed to lift upwardly on the fulcrum pin 22 thereby continuously urging the lever 18 upwardly to lift the head 14 off of the buck 13 at all times except when the press is at 55 work applying pressure. The spring 26 exerts sufficient tension to steadily maintain the position of the fulcrum pin 22 during the back and forth swing of the head 14 but readily yields to the pressure applying means 60 forming part of this invention, said means being optional in the form of foot operated mechanism or power means.

As hereinbefore referred to, a feature of this pressing machine resides in its inherent simple design and optional foot or power

pressure developing mechanism or jaw-operating means for working the press. Two forms of jaw-operating means are described first a motor-driven press, and second a pedal-operated press. In other words, the manufacturer builds one and the same type of press in accordance with the plans of this invention regardless of whether the customer intends to purchase a power press or a foot press. The same principal parts of the machine are 75 used throughout for either a foot or a power press, the principal difference in construction being of such nature that in assembling the machine, either type, foot or power, is set up with the option of a set of flat jaws or 80 V-shaped jaws, or jaws of any desired shape.

A pedal arm 28 is provided with a foot piece 29 and is pivoted on the fulcrum pin 21 on the lower end 20 of the press lever. The pedal arm 28 is integrally formed with 85 a toggle link 30 which pivotally joins at 31 with an upper toggle link 32. The links 30 and 32 constitute a vertically swinging toggle disposed centrally between the frame plates 10; and this toggle 30—32 is employed 90 in constructing either type of press, foot or power operated. The bell crank pedal 28—30 is therefore carried free of the frame by mounting it on the lower inner end of the press lever 18—20 so that the pedal 28 is 95 adapted to undergo a compound motion downwardly and rearwardly with the press lever arm 20.

Assuming that the manufacturer is assembling a power press, reference is then made 100 to the first three views of the drawing wherein is disclosed a simple type of pressure developing fluid motor which operates from the expansive power or force of air pressure or from the steam employed to heat the press 105 jaws. A motor bellows or diaphragm housing 34 is anchored to brackets 33 cast integrally on the inside of the frame plates; and the housing 34 contains a diaphragm or other fluid-pressure motor 35 which expands 110 to produce a down thrust through the toggle 30—32, and contracts to remove the force therefrom. The diaphragm 35 may be of any suitable type but is shown as the corrugated cylindrical bellows type, and the lower 115 movable diaphragm end is fitted with a connecting rod 36 projecting through the housing and is connected by a pin 37 to the upper end of the toggle link 32. The axis of the power motor 35 is in alignment with the axis 120 of the toggle as well as the lower lever fulcrum pin 21 and the power of the motor is delivered vertically downwardly directly onto the lower end of the press lever which in turn quickly clamps the head 14 tightly onto 125 the work and buck.

A pipe 39 connects the diaphragm with the steam pipe 16 or the pipe 39 may connect direct with the steam feed line 15 from the boiler if desired, but it is preferable to draw 130

steam directly from one of the pressing jaws for the purpose of hastening the circulation of steam through the said pressing jaw or jaws to maintain high temperature therein.

5 A throttle or normally-closed inlet valve 40 is included in the pipe 39 and carries the usual spring closed valve stem 41 which is directed rearwardly in alignment with an adjustable screw 42 carried in the press lever

10 18. The screw 42 is adjusted to depress the valve stem 41 and open the valve 40 just as the head 14 completes its forward or press-closing stroke; and thereupon steam flows from a boiler or from one of the pressing

15 jaws, or from any fluid pressure supply directly into the bellows 35, the result of which is to instantly expand the bellows with great force thereby pushing the connecting rod 36 downwardly with great force to produce high

20 pressure between the jaws.

As long as the head 14 stands in contact with the work, the motor means 35 continues to deliver pressure through the toggle onto the press lever because the inlet valve is held open and the fluid motor remains connected to the motive fluid supply line during the pressing operation. This power press is safe because final high jaw compression is not applied by locking open the inlet valve 40 until after the head is close to the press buck and hence the operator's hands are out of danger by that time.

Foot operated kick-off and exhaust control means are provided for the purpose of opening the press; and to this end an exhaust valve 44 is included in the pipe 39 and has the usual exhaust port 45 out through which steam discharges. The valve is controlled by a spring closed arm 46 which is oscillated by a rod 47 connected with a kick-off and exhaust pedal 48 pivoted in the lower part of the press frame. The kick-off pedal is pivoted on a pin 49 and the rear end of this pedal is provided with a lift bracket or lug 50 disposed directly underneath the pedal arm 28 as observed in Figure 2. By depressing the pedal 48, the rod 47 is first lifted to swing the valve arm 46 upwardly and allow the motive fluid to discharge from the fluid-pressure motor thereby permitting the motor means to return to its original non-pressing position; and immediately thereafter the lift lug or lost-motion means 50 impinges upwardly against the pedal arm 28 to break the toggle to the position shown in dotted lines in Figure 1 whereupon the head quickly opens and the buck is exposed for the removal of the work.

As the press lever 18 tilts rearwardly, the spring pressed throttle valve stem 41 closes thereby terminating the supply of steam to the diaphragm; and similarly as the operator removes his foot from the pedal 48, the valve arm 46 immediately closes the exhaust valve, and both valves now stand at rest closed

ready for the next operation. While a fluid pressure type motor is shown, other motor means may be used.

Referring to Figure 4, a description will be given of the same pressing machine less the power unit whereby the manufacturer is enabled to economically assemble a purely foot press and supply the trade with a less expensive press where it is required. In the foot operated cuff and neck band press shown in Figure 4, the motor means unit 34-35 is omitted and a separate bracket 52 is bolted directly onto the frame brackets 33 which reaches downwardly where it connects with the upper end of the toggle 32 with a pin 53. The position of the pin 53 in the foot press is identical to the position of the pin 37 in the power press and therefore the same toggle and pedal structure is employed. The manufacturer employs the extra brackets 52 when constructing a purely foot operated machine.

In the operation of the power press, the head stands normally open and rearwardly as shown in Figure 1 and the operator places the work upon the buck 13 whereupon he delivers, by foot power, an angular movement against the pedal 29 designed to thrust rearwardly and downwardly thereon to swing the head 14 forwardly across the buck into alignment therewith; and as the toggle 30-32 reaches straight-line position, the swingable upright is thrust downwardly and compression is developed between the jaws by the motor means or by action of the pedal or by action of both as hereinbefore described.

The operation of the foot press in Figure 4 is carried out in the same manner except that, after the head 14 reaches overlapping position with the buck, the operator is required to press somewhat harder on the pedal 29 in order that the straightening action of the toggle 30-32 overcome the spring 26 to permit compression to be developed between the ironing jaws.

Initial foot pressure applied to pedal 29 imparts an initial forward swing to the head 14 since toggle link 32 at first braces itself against pivot pin 31 to resist straightening motion. Thus the pedal tends to close the press, i. e. swing the head 14 over the buck 13. Thereafter the toggle 32-30 must by necessity start its straightening action because the lever 18 has come to rest. This straightening action draws the head down upon the buck.

The compound-motion pivots or bearings 21 and 22 which carry the upright 18 are specially mentioned because they allow the swingable-upright-head-carrying arm, lever or frame 18 to undergo two motions to wit, an up-and-down (vertical) motion and a pivotal back-and-forth (lateral) motion. These two movements of the upright 18 impart a characteristic compound two-direction freely-floating bodily motion to the press

head 14 which affords extended visibility of the buck because the head rises and throws off to the rear of the buck to fully expose the latter and better enable the operator to lay out the work on the lower press jaw.

As the compound-motion pivots 21 and 22 rise in relation to the frame 10, one of the pivots say 21 swings laterally toward the front of the press. This action tends to tilt 10 upwardly the front edge of the press head 14 as it moves back which tends to further expose and clear the buck to the view of the workman who operates the press. The pivot 21 therefore both rises and moves laterally 15 in the press frame and the other pivot 22 also rises in the frame because said pivot 22 is carried on the bell crank arm 24 which is itself pivoted in the frame.

It is seen that the lower portion of the 20 upright head-supporting press lever 18 has correlated with it, means including the two spaced compound-motion pivots 21 and 22, one above the other, for movably supporting and guiding it in a manner to afford a 25 bodily movement in relation to the press frame 10, and by bodily movement is meant that the press lever 18 in its entirety is capable of a guided floating displacement relatively to the frame, although the lever 18 30 is pivotally supported in the frame. The pedal 28 imparts bodily reciprocating movement to the press lever 18 which is carried by suitable operating loose-motion connections including the toggle 30-32 and arm 35 24 and pivot 21 established between the stationary press frame 10 and the compound-motion press lever 18, and the motor means 34 is optional.

What I claim is:

40 1. A press comprising in combination, a frame and press jaws; a vertical press lever standing behind the frame and parallel thereto, the upper end thereof reaching forwardly and fixed to one jaw, and the other 45 end thereof curved forwardly into the frame under the jaws; a movable pivot bearing means carried in the frame on which the press lever is pivotally supported, means to swing the press lever on the bearing to open 50 and close the press jaws, and means to force the press lever down to produce jaw compression.

2. A press comprising in combination, a 55 frame and press jaws; a vertical press lever standing behind the frame and parallel thereto, one end thereof reaching forwardly and fixed to one jaw, and the other end thereof curved into the frame; a movable pivot bearing carried in the frame on which the 60 press lever is pivotally supported, a pedal carried on that end of the press lever which is curved into the frame, mechanism 65 cooperating with said pedal adapted to swing the lever to close the press, and means co- operating with the mechanism to enforce

vertically downward movement of the press lever to produce jaw compression.

3. A press comprising in combination, a frame and press jaws; a vertical press lever standing behind the frame and parallel thereto, one end thereof reaching forwardly and fixed to one jaw, and the other end thereof curved into the frame; a movable pivot bearing carried in the frame on which the press lever is pivotally supported, a pedal carried on that end of the press lever which is curved into the frame, a toggle standing vertically in the frame parallel to the press lever, support means on the frame pivotally carrying the upper end of the toggle on the frame, the lower end of the toggle comprising a link integrally formed with the pedal aforesaid, and said toggle moving into straight line by operation of the pedal thus swinging the press lever and tilting it down to close the press.

4. A press as defined in claim 3 but further characterized by a motor connected with the support means which carries the upper end of the toggle and which produces a 90 thrust through the toggle to produce jaw compression.

5. A press comprising in combination, a frame and press jaws; a press lever standing vertically in the rear of the frame, and having upper and lower press lever ends extending forwardly and terminating in alignment above and below the vertical longitudinal axis of the frame and jaws, the upper press lever end being anchored to one jaw to open 100 and close the press; pivotal means supporting the press lever on the frame, means co-operating with the lower lever end to swing the press lever, and means to bring the jaws together under compression.

6. A press comprising in combination, a frame and press jaws; an upright press lever standing at the rear of the frame, and having upper and lower press lever ends extending forwardly and terminating in alignment above and below the vertical longitudinal axis of the frame and jaws, the upper press lever end being anchored to one jaw to open 110 and close the press; pivotal means supporting the press lever on the frame, a device forming part of the pivotal means permitting the press lever to undergo a compound swinging and vertical movement, means co-operating with the lever end to swing the press lever to execute one of the movements, 120 and means to force the press lever longitudinally to execute the other movement.

7. A press comprising in combination, a frame and press jaws; a press lever standing uprightly in the rear of the frame, and having upper and lower press lever ends extending forwardly and terminating in alignment above and below the vertical longitudinal axis of the frame and jaws, the upper press lever end being anchored to the upper jaw to

open and close the press; a pedal carried on the lower end of the press lever and mechanism cooperating therewith to swing said lever, a movable pivot bearing in the frame 5 on which the lever is pivoted, means cooperating with the pivot bearing to permit a compound swinging and vertical movement of the press lever, and means cooperating with the mechanism to move the press lever 10 down after the press closes to produce jaw compression.

8. A press comprising in combination, cooperating press jaws carried on a frame, a yieldable pivot bearing mounted in the frame; a vertical press lever placed to the rear of the frame and with its upper end reaching over and being anchored to one of the jaws, said press lever being mounted on the yieldable pivot bearing and the lower end 20 of the lever bent inwardly and terminating centrally within the frame underneath the jaws; means acting to normally urge upwardly on the yieldable pivot bearing and press lever to separate the jaws, a toggle including links disposed parallel to the press lever, one link of the toggle being connected with the lower bent end of the press lever, means carried by the frame holding the other end of the toggle in operative position, 25 and means to simultaneously swing the press lever and straighten the toggle.

9. A press as defined in claim 8, but further distinguished by motor means connected with one end of the toggle and adapted to exert force thereon to produce jaw compression, and automatic control means actuated by a moving part of the press which initiates the motor means after the press is closed.

10. A press comprising in combination, operating press jaws carried on a frame, a yieldable pivot bearing mounted in the frame; a vertical press lever placed to the rear of the frame and with its upper end reaching over and anchored to one of the jaws, the press lever being mounted on the yieldable pivot bearing and the lower end of the lever being directed inwardly and terminating centrally within the frame underneath the jaws; means acting to normally urge upwardly on the yieldable pivot bearing and press lever to separate the jaws, a toggle disposed parallel to the press lever, one link of the toggle being connected with the lower bent end of the press lever; a pedal integral with that aforesaid link of the toggle which is connected with the lower end of the press lever, said pedal and link thereby constituting a bell crank which swings the lever and straightens the toggle; and support 50 means pivotally holding the upper end of the toggle in operative position.

11. A press comprising in combination, a frame and press jaws, a bell crank pivoted in the frame, a press lever carrying one of the jaws and pivoted on one end of the bell

crank and means adapted to swing it to open and close the press, spring means acting on the other end of the bell crank to lift the press lever to obtain jaw separation, and means cooperating with the press lever to overcome the spring means and produce jaw compression. 70

12. A press comprising in combination, a frame and press jaws, a bell crank pivoted in the frame, a press lever carrying one of the jaws and pivoted on one end of the bell crank and adapted to swing to open and close the press, spring means acting on the other end of the bell crank to lift the press lever to obtain jaw separation; said press lever disposed vertically to the rear of and parallel to the frame, its upper end curved forward and attached to one jaw, its lower end curved forward inside the frame; a toggle with one link pivoted in the frame and its other link pivoted to the lower end of the press lever, and a pedal including means to swing the press lever and straighten the toggle. 75

13. A press comprising in combination, cooperating pressing jaws, a pair of vertically standing spaced frame plates, one of the said jaws having its edges anchored to the upper ends of the frame plates to hold said plates in rigid spaced relation, a base on which the lower ends of the frame plates are anchored to hold the plates in rigid spaced relation, a vertical press lever standing to the rear of the frame, a compound motion pivot bearing support carried by the frame on which the press lever is pivotally carried, 100 and means within the frame by which the lever and pivot are swung to open and close the press and moved vertically to produce jaw compression. 95

14. A press comprising in combination, cooperating pressing jaws, a pair of vertical standing spaced frame plates, one of the said jaws having its edges anchored to the upper ends of the frame plates to hold said plates in rigid spaced relation, a base on which the lower ends of the frame plates are anchored to hold the plates in rigid spaced relation, an upright press lever standing at the rear of the frame, a compound motion pivot bearing support carried by the frame on which the press lever is pivotally carried, a pedal carried on the lower end of the press lever to swing the lever, motor means mounted above the pedal and supported by and between each frame plate, and a connection between the motor means and press lever to force down on the lever and compound motion pivot bearing to produce jaw compression. 110 115

15. A press as defined in claim 14 in which the connection between the motor means and the press lever is a toggle which simultaneously straightens as the pedal swings the press lever. 120

16. A press comprising in combination, a 125

- frame, cooperating V-shaped cuff and neck band jaws one of which has its edges secured to the frame, a vertical lever standing to the rear of the frame with its upper end curved forwardly and anchored to the apex of the other jaw, a compound motion pivot bearing mounted in the frame upon which the lever is pivotally mounted, the lower end of the lever being curved inwardly and terminating within the frame in vertical alignment with the apices of the press jaws, means to swing the lever to open and close the press, and means to force down the lever and to produce jaw compression.
17. A press comprising in combination, a frame, cooperating V-shaped cuff and neck band jaws one of which has its edges secured to the frame, a vertical lever standing to the rear of the frame with its upper end curved forwardly and anchored to the apex of the other jaw, a compound motion pivot bearing mounted in the frame upon which the lever is pivotally mounted, the lower end of the lever being curved inwardly and terminating within the frame in vertical alignment with the apices of the press jaws, means lifting up on the lever to normally maintain jaw clearance, means to enable the operator to close the press, motor means mounted in the frame under the jaws in alignment with the vertical axis of the apices of the jaws, and a connection from the motor to the lower end of the press lever.
18. A press comprising, a frame consisting of two spaced parallel vertical parts, a jaw secured to the upper end of the frame and a movable jaw placed thereabove, a bracket ear carried by each frame part on the inside thereof in horizontal alignment, a detachable member bolted to the bracket ears and disposed between the frame parts, a press lever standing vertically behind the frame and having its upper end anchored to the movable jaw, a movable pivot carried movably in the frame and on which the press lever is pivotally supported, resilient means acting on the movable pivot to lift upwardly on the press lever, a force transmitting link disposed vertically in the frame and having its upper end connected with the detachable member, and means cooperating with the press lever and lower end of the link to swing the lever on the movable pivot to close the press and to depress the movable pivot in the frame to produce jaw compression.
19. A press comprising a pair of press jaws one above the other and a frame, a movable bearing carried in the frame; a press lever mounted in upright position on the movable bearing with its upper end anchored to the upper jaw, and its lower end terminating directly underneath the jaws, and including a bend by which the lever extends from the upper jaw to its terminating point, and means to swing the upper end of the press lever forward on the movable bearing to close the press; a fluid-pressure motor means carried in the frame directly between the jaws and the lower end of the press lever, a fluid-pressure pipe extending downwardly and connecting one jaw to the motor means, a throttle and exhaust valve means included in the pipe between the jaw and motor means, means including the aforesaid press lever to automatically open the throttle valve when the press lever swings forwardly, means to open the exhaust valve, and a vertical link with its upper end attached to the motor means and its lower end operatively connected to the press lever to thrust downwardly on the lever and displace the movable bearing and produce jaw compression.
20. A garment or ironing press comprising a frame, a press head and buck, means carried by the frame and to which a toggle-receiving device is secured, upright lever means behind the frame and having its upper end attached to the press head, bearing means spaced apart on the upright lever means, a means cooperating with one of the bearing means to mount the upright lever means in the frame for a compound vertical and rearward swinging movement in respect to the frame, pedal means pivotally mounted directly on the other bearing means on the lower end of the upright lever means, and a toggle having its upper link pivoted on the device and its lower link integral with the pedal means to swing the upright lever means and jaw thru said compound movement.
21. A garment or ironing press comprising a frame, coacting press jaws including a head and buck, jaw-operating means carried in the frame and operatively connected to the head, fluid-pressure motor means operatively connected with the jaw-operating means to produce jaw compression, a pressure supply line having a normally-closed inlet valve means and an exhaust valve suitably connected with the motor means, and means to automatically open the inlet valve after the press head reaches the buck and to hold the pressure supply line open to the motor during the ironing operation, a release pedal pivoted in the frame and operatively connected with the exhaust valve to discharge pressure from the motor to release the jaw compression; and a lost-motion means operated by the release pedal and cooperating with the jaw-operating means, whereby movement of the release pedal first opens the exhaust valve and then engages the jaw-operating means, to open the press.
22. A garment or ironing press comprising a frame, a press buck mounted on the frame, a movable press head coacting with the buck, a fluid-pressure motor means mounted in the frame under the buck, a fluid-pressure supply line connected to the upper portion of the motor means, a normal-

ly-closed automatically-operated inlet valve means above the motor means and included in the supply line, a press lever having one end attached to the press head, a toggle for opening and closing the press connected with the other end of the press lever and operatively connected with the motor means, means for closing the press head toward the buck, means operated by a moving part of the press after the press head reaches the buck for opening the inlet valve means to admit fluid pressure to the motor means and to hold the inlet valve means open to maintain the supply line open to the motor means 10 to exert force through the toggle to hold the press resiliently closed by fluid pressure during the ironing operation, an exhaust valve means also above the motor means and mounted separately from the inlet valve 15 20 means and in communication with the upper portion of the motor means, a release pedal pivoted on the frame, and a link operatively connecting the release pedal with the exhaust valve means by which the operator depresses the pedal to open the exhaust valve means to release the fluid pressure from the motor means whereby the press is opened.

23. A garment or ironing press comprising a frame, and a cooperating press head 30 and buck, an upright member at the rear of the frame and having its upper end attached to the press head and its lower end terminating under the buck, upright toggle means disposed under the buck and having its lower 35 end pivotally connected with the lower end of the upright member and its upper end pivoted on the frame under the buck, pivotal means below the buck and intermediate the ends of the upright, means on the frame co-operating with said pivotal means affording a swinging action for the upright member through a compound movement, means urging upwardly on the upright member tending to open the press, and operating means 40 45 for actuating the upright toggle means to draw said press head forwardly and downwardly to close the press and to produce compression between the head and buck.

24. A garment or ironing press comprising a frame, a press buck thereon, a movable press head, an upright at the rear of the frame and having its upper end directed forwardly and attached to the head and its lower end directed into the frame under the buck, pivotal means on the upright below the buck, means on the frame operatively connected with the pivotal means whereby said upright and press head swing thru a compound movement, toggle means having 50 55 60 65 its upper end pivotally connected on the frame under the buck and its lower end operatively connected with the lower end of the upright, pedal means to actuate the toggle means to effect the swinging of the upright in the frame to swing the head for-

wardly and to draw downwardly thereon to close the press, and means urging upwardly on the upright to open the press.

25. A garment or ironing press comprising spaced upright members forming a frame, a press buck mounted on the frame, a press head to coact with the buck, an upright lever at the rear of the frame and the lower end of which projects forwardly into the frame between the spaced members under the buck and the upper end of the upright lever projecting outside the frame and extending forwardly above and attached to the press head, pivotal means on the upright lever below the buck, means carried on the frame and operatively connected to the pivotal means on the upright lever whereby said upright lever may swing thru a compound movement, an operating toggle having its upper link pivoted on the frame under the buck above the lower end of the upright lever and extending downwardly when moved toward straightened position and having its lower end pivotally connected with the lower end of the upright lever, means urging upwardly on the upright lever to open the press, and pedal means associated with the toggle to actuate it toward straightened position to draw downwardly on the upright lever.

26. A garment or ironing press comprising an upstanding frame, a press buck on the upper end of the frame, a movable press head above the buck, an upright at the rear of and being longer than the frame and having its upper end directed forwardly and attached to the head and its lower end directed forwardly into the frame at the lower end of said frame and into position under the buck, pivotal means on the long upright below the buck, means inside the frame cooperatively related with the pivotal means to afford a vertical and back and forward movement of the upright and the press head, toggle means having its upper end pivotally connected within and on the frame under the buck and having its lower end operatively connected with the lower end of the long upright, and means to straighten the toggle to swing the press head forwardly and to force downwardly on the upright to produce high compression between the head and buck.

27. A garment or ironing press comprising a frame, a press buck thereon, a movable press head, a swingable upright at the rear of the frame and having its upper end directed forwardly and attached to the head and its lower portion directed forwardly into the frame under the buck, pivotal means on the swingable upright intermediate the ends thereof and below the buck, means on the frame below the buck and operatively connected with the pivotal means on the upright to operatively support and guide said upright thru a compound movement, an upright toggle comprising links pivotally connected

together and having its upper link pivoted within and on the frame under the buck and its lower link pivotally connected to said lower portion of the upright which projects 5 into the frame, and means to actuate the toggle toward straightened position to swing forwardly the upper end of the upright and draw downwardly thereon.

28. A garment or ironing press comprising a frame, a press buck thereon, a movable press head, an upright at the rear of the frame and having its upper end directed forwardly and attached to the head and its lower end directed into the frame under the buck, 10 pivotal means on the upright below the buck, means within and carried on the frame operatively connected with the pivotal means to support the upright and afford a bodily swinging action of the upright thru a compound movement, toggle means having its lower end operatively connected with the lower end of the upright, means to actuate the toggle means, and a fluid-pressure motor means including a connecting rod pivoted to 15 the upper end of the toggle means and extending downwardly and acting thru the toggle means to force downwardly on the upright to produce high compression between the head and buck.

29. A garment or ironing press comprising a frame, a press buck carried on the frame, a press head above the buck, an upright means, and means mounting the same in the frame for swinging and bodily movements, said upright means having its upper end extended forwardly and attached to the press head, the lower end of the upright means extending downwardly to a point directly under the buck, a pedal pivotally carried by the lower 30 end of the upright means and extending forwardly from the frame, a link integral with the rear end of the pedal and extending upwardly into the frame, an upper link pivotally connected to the upper end of the first link and forming a toggle therewith, and a pivot on the frame under the buck to which the upper end of the toggle is operatively connected, whereby downward movement of the pedal straightens the toggle forwardly 35 to swing the upright means and press head forwardly and downwardly to close the press head and produce pressure on the buck.

In testimony whereof I affix my signature.

JAMES C. LEDBETTER.
